UNITED STATES PATENT OFFICE.

SAMUEL ANDREW McFARLAND, OF OAK PARK, ILLINOIS.

METHOD FOR MAKING READY PRINTING FORMS.

Application filed November 15, 1924. Serial No. 750,184.

My present invention relates to a method for making-ready printing forms, more particularly to a method for equalizing the impression on the printed sheet so that every 5 part of the form will show its true value and give a clear, distinct and sharp impression, and the invention has for its primary object to provide a method for attaining these ends that will be more expeditious and that will 10 effect a considerable saving in labor and expense in making-ready the printing forms.

Other objects will appear hereinafter.

The invention consists in the combinations and arrangements of parts hereinafter described and claimed.

The invention will be best understood by reference to the accompanying drawings forming a part of this specification, and in which,

Fig. 1 is a fragmentary view of the non-coated side of an overlay sheet;

Fig. 2 is a similar view of the coated side of an overlay sheet;

Fig. 3 is an enlarged section taken on the 25 line 3—3 of Fig. 1;

Fig. 4 shows an enlarged cross sectional view of an overlay cutting machine, this view being taken on the line 4—4 of Fig. 5; and

Fig. 5 is a front elevational view of an overlay cutting machine of the type preferably employed in cutting away the coating of the overlay sheets.

In making-ready printing forms, it is a 25 common practice to trace out the "low spots" or impressions on the overlay sheet, and then to build up the same by adding sheets to the "low spots" to obtain an even impression. No form or engraving is so perfectly true

and level that when inked in it will show a clear and perfect impression. It is always necessary that the form be increased at some places and reduced at other places until every part thereof shows its true value

45 clearly, distinctly and sharply. In order to compensate for the inequalities, it is the common practice, as already intimated, to add thin sheets to the "low spots" in the overlay sheet and thereby to build up until 50 an adequate overlay is obtained.

Under my improved method, this operation is reversed. Instead of building up the low impressions, I make provision for cutting away or eliminating the high impressions. In the embodiment of my improved

method, no change in the methods of preparing the press cylinder is necessary. The form is handled the same as for the ordinary make-ready, care being taken that the cuts are all type high and that the correct 60 amount of packing has been placed on the cylinder or platen. When all is in readiness to pull the sheet for overlay, I take a coated overlay sheet on which the coating, preferably, is not less than four thousandths 65 and not more than six thousandths of an inch in thickness. This coated sheet for overlay should be of a size large enough to leave a fair margin outside of the printing. Usually a sheet having the same size or approximately the same size as the stock that is to be printed will leave sufficient margin. On this sheet for overlay, an impression is then pulled in the usual way, care, however, being taken to print on the back of the sheet, 70 that is to say, on the side or face that is devoid of coating. The impression having been thus taken on the non-coated side, it will, wherever too heavy, appear in the form of raised portions on the coated side of the 75 overlay sheet. Then in order to compensate for the inequalities in the form, I cut away these raised portions on the coated side of the overlay sheet, which raised portions are due as we have seen to a too heavy impression, and thereby equalize the impression on the printed sheet by the amount of the coating remaining on the overlay sheet.

80 In the accompanying drawings, I have illustrated by way of example, my preferred 90 form of overlay sheet and my preferred form of machine with which to cut away or eliminate the coating of the overlay sheet where the impression is too heavy.

95 In the drawings the numeral 6 denotes as a whole an overlay sheet having a non-coated side or face 7 and a coated side or face 8. An impression is "pulled" on the overlay sheet in the usual way; such impression as herein illustrated resulting in the too heavy lines 100 or impressions indicated at 9 and the light and sharp impressions as indicated at 10. The impressions 9, which are too heavy, are indicated on the reverse or coated side 8 of the overlay sheet in the form of raised 105 portions 11. This overlay sheet, therefore, is inadequate in this form since it will not compensate for the irregularities in the printing form. In order to produce an adequate overlay sheet, I therefore cut away the 110

raised portions 11 to such an extent as may be necessary to produce a level, clear and distinct impression that will correspond in all respects with the lighter impressions such as indicated at 10. The raised portions 11 may be cut away by hand through the use of a sharp knife, safety razor blade, or other suitable tools. This however is a laborious method by which to cut down the high portions and I preferably for this purpose employ my improved overlay cutting machine, the main features of which are herein illustrated.

This overlay cutting machine includes a base 12 from the opposite ends of which rise end frames 13 in which is journaled for rotation the axis of the overlay supporting cylinder 14. This cylinder is so ground that all points of its circumference are equi-distant from its axis; and it is preferably formed with the opposed end flanges 15. Extending across the face of this cylinder is a recess 16 through which extends a rock shaft 17 which has its opposite ends rotatably mounted in the cylinder flanges 15. Mounted on this rock shaft is a series of spaced-apart grippers 18 which are adapted to bind upon the cylinder the edge of the overlay sheet 6 which is applied with its non-coated side engaging the cylinder. Spring members 19 coiled about the rock shaft and engaging with the cylinder, normally urge the rock shaft into position to have the grippers binding the overlay sheet to the cylinder as illustrated in Fig. 5. One end of the rock shaft is provided with a crank 20 carrying a roller 21 which, during the rotation of the cylinder, engages with a cam 22 so as to raise the rock shaft automatically for the release of the overlay sheet. As soon as the roller 21 is disengaged from the cam 22 the rock shaft is automatically turned again to bring the grippers into gripping position.

The cylinder is revolved by means of a pulley 23 (belt therefor not shown) which is fast on the axis 24 of the cylinder. This pulley also has a hand crank 25 by means of which the cylinder may be manually revolved. For the purpose of cutting off the raised portions on the overlay sheet the machine is equipped with cutting tools 26 of which in the present embodiment three are shown. Each of these cutting tools has a plurality of spirally extending knives or blades 27. Each of these cutting tools has an axis 28, the opposite ends of which are supported in journal boxes 29 which are slidably arranged in the end frames 30 which rises from the base at the inner sides of the frames 13 as shown in Fig. 5. Each of the journal boxes has combined therewith an adjusting screw 31 which is operatively connected in the end frame and which carries a knurled disc 32 whereby to be operated by

hand. These cutting tools, therefore, are supported about the cylinder in parallelism to the surface thereof and each of the cutting tools is adapted because of its mounting to be adjusted either towards or away from the cylinder and each of the cutting tools, moreover is adjustable independently of the others. As clearly shown in Fig. 5 one of the cutting tools may have its cutting knives 27 coursing in a spiral direction that is opposite to the directions of the knives of the other cutting tools. Thus in Fig. 5, it will be seen that the middle cutting tool has its spiral knives 27 coursing oppositely to the spiral directions of the top and bottom cutting tools. Under this arrangement, the raised portions on the overlay sheet may be attacked from opposite directions with a slicing motion, so that they will be cleanly and accurately cut or sliced off. Adjustably secured in the frames 30 immediately in advance of each cutting tool, is a brush 33 which engages the overlay sheet as it travels around with the cylinder and eliminates substantially all the air from under the overlay sheet. These brushes make the overlay sheet hug the cylinder tightly so that the cutting tools will cut off only the raised portions on the overlay sheet.

The cylinder is driven in one direction while each of the independently adjustable cutting tools is driven in a direction opposite thereto. To accomplish this the axis of the cylinder is provided with a large gear 34 which drives the intermediate gears 35 through which gears 36 attached to the axes of the cutting tools are driven. The cylinder is driven at a slow speed while through this system of gearing the cutting tools are driven at a fairly high speed.

In making-ready the printing form in the usual way it is often necessary for experienced, highly skilled workers to labor for an entire day or more in order to produce an adequate overlay sheet; whereas by making the overlay sheets on coated paper in accordance with my method as herein described and by employing the overlay cutting machine as herein described an adequate overlay sheet may be very quickly produced. In extreme cases where the inequalities in the printing form are very pronounced, it may be necessary to make two or more overlay sheets in order to compensate fully for all of the inequalities of pressure.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new, and desire to secure by Letters Patent is:

1. The herein described method of making-ready printing forms which consists in taking the impressions of the form on the obverse side of an impression sheet capable of showing, where the impressions are too heavy, raised portions on its reverse side;
- 10 and in reducing the raised portions to corresponding superfine dimensions from the face of the reverse side.
2. The herein described method of making-ready printing forms which consists in taking the impressions on the obverse side of an overlay sheet having a coating on the reverse side capable of showing by means of raised formations from the face thereof where the impressions on the obverse side are too heavy; and in reducing the raised formations to corresponding superfine dimensions from the face of the coating.
- 20
3. The herein described method of making-ready printing forms which consists in taking the impressions on a body in sheet form;

such a body being characterized by having a reverse side which will indicate by raised formations where the impressions are too heavy; in attaching the body to a support with the raised formations facing outwardly; and in reducing the raised formations by rapidly revolving slicing knives to corresponding superfine dimensions from the face of the reverse side.

4. The herein described method of making-ready printing forms which consists in taking the impressions on a body in sheet form; such a body being characterized by having a coating on its reverse side capable of showing by raised formations where the impressions on the obverse side are too heavy; in attaching the body to a support with the raised formations facing outwardly; and in reducing the raised formations by rapidly revolving slicing knives to corresponding superfine dimensions from the face of the coating.

In testimony whereof I have signed my name to this specification.

SAMUEL ANDREW McFARLAND.
